UNITED STATES PATENT OFFICE.

DAVID H. EBINGER, OF COLUMBUS, OHIO, ASSIGNOR TO THE D. A. EBINGER SANITARY MFG. CO., OF COLUMBUS, OHIO, A CORPORATION OF OHIO.

WATER COOLER.

Application filed October 16, 1926. Serial No. 141,927.

This invention relates to an improved mechanically refrigerated water cooler, and has for an object the provision of a cooler especially designed for supplying drinking water in many places, such as public buildings, hospitals, theaters, stores, office buildings, mills and factories, the construction of the cooler being such as to provide for an adequate supply of cooled water at even temperatures for a relatively prolonged period of use and to secure this end at low cost and in a perfectly sanitary manner.

Among other objects of the invention are: The provision of a heat insulated casing of improved design for receiving in a compact and orderly manner the water cooling coils of the apparatus, in providing said casing with removable panels or door sections, whereby access to the coils is obtained in a convenient and simple manner and without interference with the adjacent fountain or faucet construction of the cooler; in constructing the cooler so that there will be but very little exterior surface upon which moisture accumulation and condensation can appear, and in constructing the casing so that such exterior condensation that may be present will be confined and collected within the interior of the casing and prevented from running down and marring the appearance of the exterior walls of the casing proper; in enclosing the drain pipe of the water fountain or faucet within the walls of the casing to prevent moisture accumulation on the walls of said drain pipe and also to produce a cooler of pleasing and finished appearance wherein exteriorly viewable pipes are in the main dispensed with and an improved appearance imparted to the cooler as a whole; and in various other features of design and construction hereinafter specifically pointed out and set forth in the following claims.

In the accompanying drawings, forming a part of this specification, and in which similar characters of reference denote like and corresponding parts throughout the several views thereof:

Figure 1 is a side elevation of a mechanical water cooler constructed in accordance with the principles of the present invention,

Figure 2 is a vertical longitudinal sectional view taken through the cooler,

Figure 3 is a horizontal sectional view on

the line 3—3 of Figure 1, disclosing the top of the cooler casing in plan, 55

Figure 4 is a horizontal sectional view taken through the casing on the line 4—4 of Figure 2,

Figure 5 is a detail vertical sectional view on the line 5—5 of Figure 2, disclosing more particularly the faucet or bubbler construction. 60

In the specific form of the invention herein selected to illustrate and disclose the features and principles of the invention, the numeral 1 designates the casing of the cooler. This casing is substantially of cubical form and includes an enclosed hollow body formed from joined sides, top and bottom walls. In the preferred construction of the casing the latter includes an outer tank formed preferably from sheet metal, and comprising a bottom wall 2, provided with an upstanding marginal flange 3, to which is secured the lower edges of vertical sheet metal side walls 4, the wall 2 being supported above a base or floor surface at a suitable elevation by the provision of rigidly mounted supporting legs 5. To the upper edges of the walls 4 there is secured a horizontally disposed top wall 6, provided in this instance with downturned flanges at the marginal edges thereof, indicated by the numeral 7, which are suitably secured to the upper edges of the walls 4, whereby the outer tank prevents a rigid, 70 stable homogeneous construction. 80

The casing is also formed to comprise an inner metallic tank formed to include a bottom wall 2^a, upstanding side walls 4^a, and a top wall 6^a, suitably united to produce a liquid 90 containing non-corrosive structure. The walls of the inner and outer tanks of the casing are spaced, as shown in Figure 2, for the reception of a hidden heat insulating filler 8. In a standard commercial embodiment of the invention this filler takes the form of cork board which has been fitted in a heated mixture of bitumen or a substance known by the commercial name of "Hydroline". This insulation is closely inserted between the adjacent walls of the inner and outer tank of the casing so as to completely fill the space existing between them and to minimize heat translation or exchange between the relatively cool or cold temperatures prevailing within the liquid containing 100 105

chamber 9 of the casing and the relatively higher temperatures of the atmosphere surrounding the casing, in order that temperature losses by reason of insulation may be 5 kept as low as is practicable.

The top walls 6 and 6^a of the casing are provided with registering openings 10 for the reception of a removable cover section 11. This section extends substantially across 10 the full width of the cooler, as shown in Figure 3, and is adapted to be secured in place by the provision of fastening screws 12. The removal of the section 11 permits of the insertion within the chamber 9 of the tank the 15 mechanical refrigerating unit, designated by the numeral 13. This unit may be any one of several standard types now in general commercial use and known by the trade-name of "Frigidaire" or "Kelvinators". These units, 20 as usual, comprise a tank 14 in which is received for expansion sulphur dioxide (SO₂) or other equivalent refrigerant. This tank is suitably secured to the side walls 4^a to occupy the horizontal position disclosed in 25 Figure 2, and depending from the tank is a coil 15, commonly known in the trade as the "boiler or expansion coil". As usual, this coil operates to extract heat from the body of water contained within the casing chamber 30 9 and in operation a frost or ice accumulates on the outer surfaces of the coil, due to the low temperatures thereof, which chills the temperature of the water within the chamber 9 so as to correspondingly lower the working 35 temperature of a water coil 16, also located within the chamber 9 and submerged in the water normally carried therein. It will be observed that the lower end of the coils 15 are spaced from the wall 2^a, so as to 40 allow for expansions and frost accumulations on the part of this coil without interference from the wall of the casing. One of the side walls 4-4^a of the casing is provided with a vertically disposed opening 17 for the reception 45 of an access plate 18, which is secured in place by means of removable screws 19. By the provision of the plate 18 access is easily obtained for the purpose of controlling the operation and adjustment of the inlet and 50 outlet valves 20 provided upon one end of the tank 14 for controlling the flow of the refrigerant. Thus, through the provision of the cover section 11 and the access plate 18, the servicing of the mechanical refrigerating 55 unit can be easily and quickly accomplished without interfering with the remaining unit of the cooler.

The water coil 16 is preferably formed 60 from copper tubing, which is self draining and is wound to assume the spiral configuration disclosed particularly in Figures 2 and 4. The lower end of the coil 16 is connected with a water inlet fitting 21, provided in the bottom wall of the casing, which fitting, in 65 turn, is adapted to be connected with a suit-

able source of drinking water supply, such, for example, as a city water main. The upper end of the coil 16 is connected with a vertically extending pipe 22, which projects through the top of the casing and is provided 70 in this instance with a manually operated self closing valve 23, the upper end of the pipe communicating with an angularly disposed water jet 24 provided in what is known as an angle stream bubbler 25, one or more 75 of which being carried in connection with the top of the cooler. By reason of the disposition of the jet 24 with relation to the receptor or bowl 26 of the bubbler, the opening of the valve 23 permits of the ejection of 80 an arcaute upwardly, outwardly and then downwardly directed stream of water which may be either consumed directly by the operator of the fountain, or may be caught in a tumbler, glass or other receptacle as desired. It will be seen that the coil 16 is completely immersed, up to the water level indicated at 26' in the inner tank of the casing, and then due to the relatively low temperature 85 of this water, effected by the mechanical refrigerating unit, the water circulating through the coil 16 will have its temperature correspondingly lowered so as to be properly cooled and tempered for drinking purposes. Due to the manner of forming the coil 16 the 90 latter may in practice include any requisite number of feet, linearly arranged, of tubing, thus enabling quite a large quantity of drinking water to be retained at any one time within the coil, thus providing a stored supply, 95 as it were, of chilled water which may be used as required. It will be understood that other types of water outlet fittings may be connected with the upper end of the coil than that shown and specifically described herein. 100

The waste pipe 27 leading from the bottom of the bowl 26, passes through the top of the casing and between the side walls 4 and 4^a so as to be concealed from exterior view and also to minimize exterior condensation. The lower end of the waste pipe terminates within a drain cup 28, carried by the bottom of the cooler, and from which leads an outlet pipe 29. Arising from the bottom of the casing within the chamber 9 and disposed within the confines of the coil 16 is an overflow pipe 30, which determines the level of the water within the chamber 9 and prevents the tank from being overfilled with water. The lower end of the pipe 30 terminates within a water sealed compartment 31 provided in the drain cup 28 but which compartment is in communication with the outlet pipe 29. 110

The top wall 6 of the casing to one side 115 of the cover section 11 is provided with a basin or depression 32, shown more particularly in Figure 3. This basin is arranged to surround the supply and waste pipes 22 and 27 respectively of the drinking fountain, in 120 125 130

order to receive and collect the moisture or condensation which drains down the exterior surfaces of these pipes, and to lead this moisture into a downwardly directed short pipe 5 section 33, which terminates below the level of the water in the chamber 9. By this construction the condensation is confined to a comparatively small area of the cooler and is prevented from dripping or running down 10 the side walls thereof and disfiguring or marring the exterior appearance of the casing. This feature is of very considerable importance where there is a large temperature differential between that of the cooled water 15 and the exterior or surrounding atmosphere.

By the construction described there is provided a water cooler suitable for public and private buildings and residences, and wherein a high degree of efficiency is provided together with an attractive appearance. Moreover, the construction set forth enables the several units of the cooler to be manufactured and assembled with economy and facility and simplifies the servicing and adjustment of the mechanical refrigerating unit 25 when the cooler is in operation.

What is claimed is:

1. In a water cooler, a casing comprising spaced inner and outer walls separated by a 30 heat insulating filler, said walls serving to define an enclosed liquid containing tank, a mechanical refrigerating unit disposed with-

in said tank, a water cooling coil mounted within said tank and provided with means for admitting of the circulation of water 35 therethrough independently of the liquid contained in said tank, a drinking fountain connected with the upper portion of said coil and arranged to project above the top of said casing adjacent to one side of the latter, 40 a drip basin carried by the bottom of said casing, an overflow pipe arranged vertically within said tank and opening into said basin, and a waste pipe leading from said fountain to said drip basin. 45

2. In a water cooler, a casing comprising spaced inner and outer walls having a heat insulating filler provided between them, said walls serving to define an internally situated liquid containing tank, a mechanical refrigerating unit mounted within said tank, a water cooling coil arranged within said tank, a valve controlled water outlet connected with the upper portion of said coil and extending above the top of said casing 55 to one side thereof, a waste pipe leading from said outlet, a basin provided in the top of said casing and arranged adjacent to said outlet and waste pipe to collect condensation from the walls of the latter, and a conduit 60 leading from said basin to the interior of said tank.

In testimony whereof I affix my signature.
DAVID H. EBINGER.
